UNITED STATES PATENT OFFICE.

JOHN A. MILLIKEN, OF NEW YORK, AND CHARLES H. MILLIKEN AND EDWARD D'AMOUR, OF BROOKLYN, ASSIGNEES OF ONE-FOURTH TO CHARLES F. SMITH, OF BROOKLYN, NEW YORK.

TICKET-PRINTING MACHINE.

SPECIFICATION forming part of Letters Patent No. 410,555, dated September 3, 1889.

Application filed May 2, 1888. Serial No. 272,568. (No model.)

To all whom it may concern:

Be it known that we, JOHN A. MILLIKEN, of the city, county, and State of New York, and CHARLES H. MILLIKEN and EDWARD D'AMOUR, of Brooklyn, in the county of Kings and State of New York, have invented certain new and useful Improvements in Ticket-Printing Machines; and we do hereby declare that the following is a full, clear, and exact description of our invention, such as will enable others skilled in the art to which it appertains to make and use the same.

Our invention relates to ticket-printing machines adapted to be used by ticket sellers or agents to print tickets at the time they are called for by passengers.

In our apparatus when a ticket is called for at the ticket-window the operation of a single lever by the agent will cause a ticket to be printed, fed out of the apparatus, cut off, and registered automatically.

We are aware that machines of this kind have been invented; but our particular objects are to provide a machine which embraces mechanism for operating either by electricity or by mechanical means, the construction being such that should the electrical means for operation fail at any time, either through mistake, accident, or otherwise, the mechanical means for operating will be automatically thrown into service without any loss of time or action on the part of the ticket-seller or operator. A further object is to provide an apparatus which will print a round-trip or "excursion" ticket, and which will perform this operation with as great facility as is required to print a single-passage ticket. A still further object is to prevent the use of counterfeit tickets by passengers by means for changing the inking apparatus, so that different colors may be substituted by the operator at any time. Another object is to provide a machine in which all kinds of tickets, whether whole-fare, half-fare, or excursion, are printed from the same strip. Finally to construct a machine embodying mechanism for performing all of the above-mentioned functions, which shall occupy as little space as possible, have fewest number of parts, be reliable in its operation, and re-

quire the least possible action on the part of the agent to operate it.

We have illustrated our invention in the accompanying drawings, in which—

Figure 1 represents a plan of the apparatus with the casing and a few of the parts removed. Fig. 2 is a central sectional view of the casing, showing the side elevation of the apparatus within. Fig. 3 is a similar section showing a front elevation of the apparatus. Fig. 4 is a section through a part of the frame, showing the feed-rollers and the electric and spring motors in elevation. Fig. 5 is a plan of what is shown in Fig. 4. Fig. 6 is a transverse section of the feed-rollers with the ticket-strip between them, and Fig. 7 is a detail view of the clutch mechanism used in connection with the cam-wheel.

It will be seen that in the plan view, Fig. 1, we have provided a system of levers and their connections on each side of the machine, which are exact counterparts of each other. It will therefore only be necessary to describe with particularity the mechanism on one side of the machine. These two sets of mechanism are adapted to print, respectively, whole and half fare tickets. The ticket-strip passes lengthwise through the machine midway between these two sets of mechanism, either one of which is adapted to operate upon the strip. It therefore requires but a single strip, and hence a single feeding mechanism to print either the half-fare or the whole-fare ticket.

The means for printing the excursion-ticket for either full fare or half-fare forms parts, respectively, of the two sets of mechanism, as will be hereinafter particularly set forth. The apparatus is mounted on a suitable base-plate A and covered by a casing A', having in its front face an opening A², through which the ticket, after being printed, is fed out to be finally deposited after being cut off into a receptacle A³. Frame-work of the proper character is used in different parts of the apparatus to support the shafts and other parts of the machine. In some of the figures the frame-work is broken away to show the parts which it would naturally cover.

We will now proceed to describe the mech-

anism on one side of the machine; but the same description will apply to the other, referring more particularly to Figs. 1 and 2. At the forward end of the machine, mounted 5 horizontally, are three rods B B B. These rods serve as ways for carriages B' and B². These carriages carry engraved plates or type-faces b on their under sides, which are held in place by thrust-rod b'. The latter 10 extend up through the carriages, projecting above the same some distance, and are headed, as shown in Figs. 2 and 3. Between the heads of these rods and the upper surfaces of the carriages are inserted coil-springs which 15 normally hold the rods and printing-plates in their highest position. The rods are adapted to be driven downward to carry the engraved plate or type faces to make the impression. At the forward and rear ends of 20 the carriages we have provided type-boxes b² for carrying the interchangeable dating-types. The carriage B' is connected by means of link c and bell-crank c' with a push-bar c². The push-bar extends to the outside of the 25 casing and has a button on the end to be pushed against by the operator in handling. The carriage B² has a similar connection with push-rod c³. The ticket-strip is blank on both sides and enters the machine at the rear 30 under roller z and traverses a way or channel w, which conducts it through the center of the apparatus, over a tablet, and in a horizontal plane parallel to the faces of the printing-plates, but somewhat below their normal 35 position. At the forward end and directly above the ticket-strip is suitably supported an electro-magnet D, whose armature D' has connected to it two downwardly-projecting studs d, which pass entirely through the core 40 of the magnet and serve as hammers to strike the heads of rods B whenever they are in position to be struck, and the circuit of the magnet is closed. The armature is pivotally connected with an arm D², loosely mounted on 45 the shaft D³. The length of its movement, free of the shaft, however, is limited by a pin d², playing in a notch in the hub of the arm D². The armature is drawn downward by the magnet and returned to its normal position 50 by the spring d³, encircling the shaft D³, and having one of its ends fixed to the bearing of the shaft and the other fixed to the arm D². The shaft D³ has a rocking motion controlled by magnet E and coil-spring E', which act in 55 opposition to each other. The armature of magnet E is the pivoted arm e, which is connected by a crank-arm e' to the rock-shaft, as shown in Fig. 3. When the magnet is not energized, the spring E' rocks the shaft and 60 withdraws the arm e from the magnet-pole. The arm e is pivoted at e², and has a downward extension e³, provided with a toe, which is adapted to lie against the periphery of a cam-wheel M, or away from the same, according 65 to whether the magnet E or the spring E' is the stronger. On the other end of the rock-shaft is hung an arm F, which extends down

nearly to the base-plate of the machine, where it connects with a link and pawl f and f', as shown in Figs. 3 and 5. The pawl normally engages with a ratchet-wheel f², preventing the spring-motor from operating. This motor consists of a suitable spring, and a train of gearing, the last wheel of which f³ is loose on its shaft, but adapted to be fixed thereto by pawl f⁴ engaging with a ratchet tight on the shaft. The wheel f³ gears with a pinion on an upright driving-shaft f⁵, which serves as the main driving-shaft of the feed mechanism, and is adapted to be operated either by the 70 spring-motor or an electric motor, as will be set forth. When the electric motor is operating, it is necessary that the train of wheels connected with the spring-motor should remain stationary; hence the pawl-and-ratchet 75 arrangement in connection with wheel f³. The upright shaft f⁵ carries a worm f⁶, which drives a worm-gear f⁷. The worm-gear is mounted on shaft G, carrying the upper feed-roller G'. The lower feed-roller G² is mounted 80 on a shaft G³, which is driven from the upper shaft by suitable gearing. On the vertical shaft f⁵ is fixed an armature of an electromotor H. The will thus be seen that the operation of either 85 motor will work, through the vertical shaft f⁵, to drive the feed-rollers. The shaft of the lower feed-roller is extended beyond one of its bearings, and has loosely-mounted upon 90 it a wheel M. The outer face of this wheel is provided with a cam-groove m. The wheel 95 is loose upon the shaft, but is adapted to be locked thereon by means of a sliding clutch m'. The construction of this clutch is shown 100 in Fig. 7. A sliding spline or bolt q moves longitudinally in a groove of the shaft, and 105 is adapted to enter a hole in the hub of the wheel, thus locking the wheel to the shaft. The bolt has a notch in it, in which lies a ring 110 or collar surrounding the shaft. Any longitudinal adjustment of the collar will cause a 115 corresponding movement of the bolt; hence by throwing the collar out the bolt is withdrawn from the wheel, and thus unlocks it from the shaft. The ring and bolt constitute the movable part of the clutch. In the cam-groove m an anti-friction roller, attached to a 120 pivoted lever N, runs. The lever extends to the front part of the machine and connects by means of a link with pivoted knife O. The knife plays vertically across the path of the ticket-strip and shears off a ticket after it has been fed out.

At the rear end of the machine, above and below the ticket-strip, extend two horizontal shafts I and I', mounted in suitable bearings 125 on each side of the apparatus. The shaft I has fixed upon it a sleeve carrying two fingers i and i'. The end of the finger i' is capped by insulating material, and bears against the free end of a tilting lever J. Near each end of the 130 shaft I is fixed an arm i². They extend upward and lie against the forward side of pins i³, located on the push-rods c². When the push-rod c² is operated, the shaft I is rocked

and through the finger *i* lifts the lever *J*. The shaft, the push-rod, and their connections are returned to their normal positions by the coil-spring *i'*. Push-rod *c*³ carries a sleeve *c*⁴, to which is attached a pin *c*⁵, bearing against the ends of arms *k*, fixed on each end of the shaft *I'*. The latter shaft has an arm *k'*, which extends downward and connects with a short bar *k*², which is attached at one end to a pivoted arm *k*³ and at the other to a bell-crank *k*⁴. The operation of the push-bar *c*³ causes shaft *I'* to rock and bar *k*² to reciprocate, carrying with it arm *k*³ and bell-crank *k*⁴. The second arm of bell-crank *k*⁴ is fixed to the movable part or sliding collar of clutch *m'*. The arm *k*³ bears upon finger *i'* on the shaft *I*. Push-rod *c*³ is made up of a sleeve and a solid rod, as shown, and on the sleeve is fixed a collar *c*⁶, having a lug which is adapted to engage with a similar lug on the collar *c*⁴, fixed to the push-rod *c*³. This engagement, however, only takes place when the push-rod *c*³ is operated.

The arm *J* has a dog *j* on its under side, which normally rests in a notch formed on the inner edge of the periphery of the cam-wheel *M* in an annular strip of insulating material *m*². This notch is cut through the insulating material so that the dog may have metallic contact with the wheel when it is in the notch. Another notch is cut in the periphery of the wheel *M*, in the same plane with the end of the arm *e*³. This notch is adapted to receive the end or toe of the arm *e*³ whenever it is forced into it. When the arm *J* is lifted, the movement is sufficient to carry it into contact with a metallic stop *L*, fixed in a part of the frame directly above the arm.

The feed-rollers shown in section in Fig. 6 are cut away for about one-fourth of their circumference for the purpose of stopping the movement of the strip during a short space of time while the printing is being done, and the ticket is cut off. In the figure the starting position of the rollers is shown, and during the first eighth revolution the ticket is printed, and during the last eighth the ticket is cut off. The under roller has an engraved surface, which prints a continuous design as it passes through.

The inking devices for the printing-plates in the forward part of the machine consist of four ink-reservoirs *P*, one for each carriage or plate. The reservoirs have mounted in them two rollers, which move in contact with each other. The larger one is in contact with the ink and the smaller one takes its ink from it. When the carriages make their lateral movement to the center of the machine, their engraved plates or type-faces take ink from the smaller roller. The reservoirs are fitted with spring draw-bolts in their bases to hold them in position in the machine. They are inserted into place through openings in the base-plate. The inking apparatus for the lower feed-roller is of a similar construction,

the position of the two inking-rollers being indicated in Fig. 2.

The electric circuits are as follows: The lever *J* is insulated from all parts of the machine, except when the dog *j* is in the notch of the cam-wheel *M*. The circuit from one side of the generator goes to the arm *J*, thence through cam-wheel *M*, when arm *J* is down through the frame, and back to the generator. One end of the coil of magnet *E*, however, is connected with arm *J* and the other end leads off through the electric motor and thence to the frame of the machine. Hence it will be seen that when arm *J* is down the motor and the magnet *E* are short-circuited; but when it is up the magnet and motor are in the direct circuit. The printing-magnet *D* is located in a shunt around magnet *E* and the motor—that is to say, one of its terminals is connected with the stop *L*, against which the arm *J* impinges at the upper extremity of its stroke, and the other terminal is connected with the circuit on the other side of the motor. The resistances are so regulated that the current is about equally divided between the motor and magnet *E* on the one side and the printing-magnet on the other when the arm *J* strikes stop *L*.

The operation of the machine is as follows: To produce a full-fare single ticket, the push-rod *c*³ is shoved in by the operator and immediately let go. Its motion throws the carriage *B'* to the center of the machine directly beneath magnet *D* and over the ticket-strip. At the same time through rock-shaft *I* and its connections the dog *j* is lifted from the notch in cam-wheel *M*, which immediately throws a current of electricity through magnet *E* and the electromotor. Magnet *E* draws up its armature *e*, rocking the shaft *D*³ and causing arm *F* to throw the pawl *f'* into the ratchet-wheel *f*² and prevent the spring-motor from operating. At the same time the electromotor commences to rotate and turn the feed-rollers. On account of the cut-away portion of the feed-rollers their first motion will not cause the movement of the strip, and just before the rollers grasp the strip the arm *J* makes contact with the stop *L* and shunts a portion of the current through the printing-magnet *D*. This magnet then draws its armature down and forces one of the studs *d* against the head of the push-rod *b*', making the impression of the engraved plate or type-faces upon the strip. As the push-rod *c*³ is immediately released after being pushed in, the arm *J* quickly falls away from stop *L* and cuts out the printing-magnet *D*, thus allowing the armature *D*' to be withdrawn by the coil-spring *d*³ on shaft *D*³. When the arm *J* falls back, the dog *j* rides upon the ring of insulating material on the periphery of the cam-wheel *M* as the said wheel turns with the feed-rollers to feed out the strip. One rotation of the feed-rollers causes the length of one ticket to be fed for-

ward; but during the last eighth of their rotation the strip does not feed, and during this space of time the cam-groove in the face of the wheel M operates upon lever N to throw 5 down the knife and shear off the ticket. When this is accomplished, one complete revolution of the cam-wheel has been completed and the dog j drops into the notch and short-circuits the motor, thus stopping the apparatus.

To produce a full-fare round-trip or excursion ticket, the operator pushes in the rod c³ and immediately lets go. The collar c⁴ comes in contact with the collar c⁶ on the rod 15 c² and carries said rod c² with it, thus sending both carriages B' and B² to the center of the machine beneath the printing-magnet and over the ticket-strip. Through rock-shaft I' and its connections the clutch controlling the 20 cam-wheel is thrown out, unlocking the wheel from the shaft, and through the arms k², i, and i' the arm J is lifted. This, as before, throws into circuit the motor and magnet E, which perform the same functions, as before 25 set forth. When arm J makes contact with the stop L, the printing-magnet drives down both of the engraved plates or type-faces on the carriages B' and B² and prints a double or round-trip ticket. The feed-rollers, which 30 have been turning, now grasp the strip and feed it forward, the cam-wheel in the meantime remaining stationary. In practice the notch in the cam-wheel will be made about one-sixteenth of an inch deep, and the length 35 of movement which the clutch is to make in order to uncouple the cam-wheel will be about three-sixteenths of an inch, so that the cam-wheel will not be unlocked until a short time after the dog j has left the notch. Therefore 40 the cam-wheel will make a slight rotation, just enough, in fact, to carry the notch beyond the dog. The wheel then stops its rotary movement and the arm J falls back, allowing the dog j to rest upon the ring of insulating 45 material. After one revolution of the feed-rollers is made the bolt forming a part of the clutch is presented to the opening in the cam-wheel and is forced into it by the coil-spring i⁴ on shaft I, acting through the 50 intermediate leverage. The cam-wheel then begins to turn with the feed-rollers. The latter, however, are beginning their second rotation. During the last eighth of this second 55 rotation the cam operates the knife and cuts off the double ticket. The notch in the cam-wheel is then presented to the dog j, and it falls into it, cutting out the motor and stopping the machinery.

For producing a half-fare ticket, the push-60 rods on the other side of the machine are used in exactly the same manner as above described for the full-fare tickets—that is to say, by pushing in the upper rod a single half-fare ticket will be produced, and by operating the lower rod an excursion half-fare 65 ticket will be produced, and whether whole or

half tickets are printed they are all made from the same ticket-strip.

If, by accident, design, or otherwise, the electric current should be stopped or the electrical apparatus fail to work in any way the operation would be as follows: The arm J would be lifted, and there being no electric current magnet E and the electric motor would not be energized, and spring E' on the 70 shaft D², which acts in opposition to the magnet E, would rock the shaft and throw the toe or arm e³ against the periphery of the cam-wheel. This rocking of the shaft would also throw arm F backward, lifting pawl f' 75 out of engagement with the ratchet-wheel f², allowing the spring-motor to come into operation. This motor, acting through its train of gearing on the main or armature shaft of the electric motor, will turn the feed-rollers 80 in the same manner as the electric motor would do. As soon as the cam-wheel M has rotated a short distance, the notch in the periphery of said wheel, which lies in the path of the toe of arm e³, is presented to said toe, 85 and the spring E' on shaft D² suddenly forces it into the notch, allowing shaft D² to be turned a corresponding distance. When the shaft turns, the pin d² comes in contact with the sleeve supporting the arm D², carries said 90 arm down, and strikes the carriage-rod in the same manner as is done when the printing-magnet operates. The motor continues to operate until one revolution is made, when the dog j drops into the notch and stops it. 95 In printing an excursion-ticket the same operation is performed by the different levers and shafts to allow two revolutions of the feed-rollers, as when the machine is operated by electricity, the means controlling this 100 double rotation of the feed-rollers being entirely mechanical.

It will be seen that by duplicating the type-carriages and their connected levers and adjusting the feed-controlling mechanism accordingly, three or more tickets may be produced from the same ticket-strip with almost 105 equal facility.

It should be observed that through the interchangeability of the ink-reservoirs and 110 their rollers the colors may be changed as many times as desirable, and different combinations of colors may be used. A change may be made every morning or every week, or at irregular intervals, so that counterfeit tickets 115 may be detected by their color, if by no other difference. With such changes in the colors 120 counterfeiting will rarely be attempted.

It is our intention to combine with our machine suitable registering devices for registering the number of each kind of ticket sold. The registering devices will preferably consist of the well-known series of numbering-disks with pawl-and-ratchet arrangement. It 125 will be operated by levers and pins connected with the push-rods. It is not deemed necessary to show these devices and their connec-

tions, as they constitute no part of the present invention.

Although we have herein referred to whole and half fare tickets and to excursion or round-trip tickets, it is obvious that these terms were simply used to express tickets of different denominations or kinds, and we do not confine ourselves to the printing of simply the particular kind of tickets mentioned.

10 The impression-plates or type-forms may be changed at will to print any kind, form, or denomination of ticket. The machine herein described, however, is particularly adapted for the printing of single or round-trip tickets 15 of both full and half values.

Having now described our invention, we claim—

1. In a ticket-printing machine, a ticket-way, channel, or tablet, one or more impression-plates or type-forms arranged on each 20 side of said way, channel, or tablet and out of printing position, in combination with systems of leverage for moving said plates or forms into printing position, substantially as 25 set forth.

2. The combination, with two independently-operated impression-plates or type-forms for printing different kinds of tickets, of a single printing-magnet, which is adapted 30 to operate in conjunction with either of said mechanisms to print any form of ticket required.

3. The combination, with two independently-operated impression-plates or type-forms for printing different kinds of tickets, of a hammer adapted to operate in conjunction 35 with either of said plates or forms to print any kind of ticket desired.

4. In a ticket-printing machine, the combination, with two carriages, each provided with engraved plates, of a push-rod for throwing one of the said carriages into a position for printing, and a separate push-rod for throwing both carriages simultaneously into a similar 45 position.

5. In a ticket-printing machine, the two push-rods, in combination with the type-carriages, the former for operating the type-carriages, and each being provided with lugs or 50 projections so arranged that one of said rods may be operated alone while the other cannot be moved without coincidentally operating its fellow.

6. The combination, herein described, with 55 two similar sets of mechanism on opposite sides of the machine, the said mechanism consisting of carriages having type-plates and a system of leverage for moving the same into a position above the ticket-strip where 60 the printing is done, of a tablet or way over which the ticket-strip passes, located intermediate of the two sets of mechanism.

7. In a ticket-printing machine, a centrally-located ticket-strip way, channel, or 65 tablet, a hammer or striking apparatus located directly above the same, two sets of printing-plates located on each side thereof,

and manually-operated mechanism for throwing the printing-plates into position to be struck by the hammer or striking apparatus 70 to drive them against the ticket-strip.

8. In a ticket-printing machine, two motors, both adapted to feed out the ticket-strip, in combination with an electro-magnet which when energized will lock one of the motors and 75 when not energized will allow a spring to unlock the same motor, as set forth.

9. In a ticket-printing machine, an electro-motor and a spring or mechanical motor, both adapted to feed out the ticket-strip, in combination 80 with an electro-magnet in circuit with the electromotor, the armature of said magnet being constantly subjected to spring or other power in opposition to the pull of the magnet, and a pawl or other locking device 85 for the spring or mechanical motor, connected with the armature in such a manner that when the said magnet is energized it will act on its armature to lock said mechanical motor, allowing the electromotor to drive the feeding mechanism, and when said magnet is not energized it will allow the power opposing the magnet to act through the armature to unlock said mechanical motor to drive the feed-rollers.

10. In a ticket-printing machine, the combination, with an electric circuit, including an electric motor, the frame of the machine, and an insulated locking-bar, as J, of a rock-shaft, as I, geared to push-rods under control 100 of the operator, whereby said arm J may be brought into contact with the frame of the machine to short-circuit the motor, substantially as described.

11. In a ticket-printing machine, a bar, as 105 J, and an electric motor for the feeding mechanism included in the same electric circuit, in combination with the feeding mechanism, the said bar being adapted to lock the feeding mechanism and simultaneously short-circuit the motor, as set forth.

12. In a ticket-printing machine, a hammer for driving the type or impression-plate against the ticket-strip, in combination with an electro-magnet and a spring, either of 115 which is arranged to operate the hammer, for the purpose specified.

13. In a ticket-printing machine, the means for mechanically driving the type or impression-plate against the ticket-strip, consisting 120 of a movable element, as M, moved by any suitable motor and provided with a notch, in combination with a spring-actuated rock-shaft carrying two arms, one of which is connected with the impression-plate and the other 125 adapted to enter said notch in the movable element and allow a rocking movement of the shaft to drive the impression-plate against the ticket-strip, substantially as described.

14. In a ticket-printing machine, a printing-magnet and an electric motor controlling the feeding mechanism, the magnet being located in a shunt-circuit to the motor, in combination with a mechanical-locking and circuit-

controlling arm, as J, for locking the mechanism which the motor drives and for switching the electric current through the motor and closing the circuit of the printing-magnet.

5 15. A knife-operating wheel and a pair of feed-rollers geared together and adapted in one rotation to feed out and cut off the length of one ticket from the ticket-strip, in combination with the push-rod c^3 , the clutch m , and 10 intermediate leverage, whereby the clutch is operated simultaneously with the push-rod to uncouple the cam-wheel from the feed-rollers and prevent its movement during the rotation of the shaft, substantially as described.

15 16. In a ticket-printing machine, two independent sets of mechanism for printing different kinds of tickets, each set consisting of a system of leverage and an engraved plate or type form operated thereby, both sets being 20 adapted to print upon the same ticket-strip, as described.

17. In a ticket-printing machine, a single way, passage, or channel for the strip to be printed upon, a pair of printing-plates or type-forms arranged on each side of said way or channel, and systems of leverage corresponding to the plates or forms of each pair for moving one or both members of each pair into position to print upon said strip.

30 18. In a ticket-printing machine, a ticket channel or tablet, a hammer located above the same, a laterally-moving plate or type-form located normally at one side of said ticket-channel or tablet, and mechanism consisting of a system of leverage for moving said plate or type-form into a position adjacent to the said ticket channel or tablet, where it may be struck by the hammer.

19. In a ticket-printing machine, a ticket 40 channel or tablet and hammer located adjacent to or above the same, a plurality of independently and laterally moving plates or type-forms, and mechanism consisting of a system of leverage for moving said plates or 45 type-forms into a position to be struck by the hammer and caused to make an impression.

20. In a ticket-printing machine, the combination, with a ticket way, channel, or tablet, of a series or plurality of impression-plates or type-forms arranged adjacent thereto, a system of leverage for throwing one of the said plates or forms into a position to print upon the ticket-strip, another system

of leverage acting in connection with the 55 first system for throwing two of said plates or forms into a similar position, a third system of leverage acting in connection with said first and second systems for throwing three of said plates or forms into a similar 60 position, and so on throughout the series, whereby any number of tickets may be printed by operating the proper system of leverage.

21. In a ticket-printing machine, the combination, with a ticket way, channel, or tablet, of a series or plurality of impression-plates or type-forms arranged adjacent thereto, a system of leverage for throwing one of the plates or forms into a position to print 70 upon the ticket-strip, another system of leverage acting in connection with the first system for throwing two of said plates or forms into a similar position, a third system of leverage acting in connection with said first and 75 second systems for throwing three of said plates or forms into a similar position, and so on throughout the series, whereby any 80 number of tickets may be printed by operating the proper system of leverage, all in combination with a striking device adapted to drive one or more of the plates or forms against the ticket-strip to make the impression, substantially as described.

22. In a ticket-printing machine, a knife 85 for severing a ticket from the ticket-strip, mechanism for operating said knife, a feeding device for feeding out the ticket-strip and connected with the knife-operating mechanism by a suitable clutch, all in combination with an actuating rod or lever, and connections between said rod or lever and clutch, whereby the operation of said rod or lever will open the clutch and disconnect the knife mechanism from the feeding mechanism, 95 thus allowing the ticket-strip to be fed out without the operation of the knife, substantially as described.

In witness whereof we have hereunto signed our names in the presence of two subscribing 100 witnesses.

JOHN A. MILLIKEN.
